mesne assignments, to King-Seeley Corpora-
tion, Ann Arbor, Mich., a corporation of Michi-
gan

Application March 17, 1937, Serial No. 131,448

4 Claims. (CL 267—1)

This invention relates to governors for internal combustion engines and more particularly to governors adapted for insertion between the carburetor and intake manifold of such an engine and actuated by changes in pressure in this manifold to govern the speed of the engine.

It is a general object of the present invention to provide a novel and improved governor of the type described.

10 More particularly it is an object of the invention to provide, in such a governor, means for adjusting the same for operation throughout a wide range of closely governed speeds.

Another object of the invention consists in the provision of novel means for adjusting both the flexibility and the resistance of the governor

20 A further object of the invention consists in the provision of novel auxiliary means for imparting a positive closing effort to the valve in wide open position without producing additional friction on the valve and its operating mechanism when near closed position where the operating forces are a minimum.

25 An important feature of the invention resides in the mechanism for simultaneously adjusting both the flexibility and the tension of the spring, together with means for separately adjusting the tension only of this spring.

30 Another feature of the invention consists in the provision of simple actuating and locking means for the adjusting device.

35 A still further feature of the invention consists in the provision of remote control mechanism for adjusting and locking the spring tensioning and resistance adjusting mechanism and which can be substituted for the before-mentioned adjusting and locking mechanism whereby the governor can be adjusted under the control of a key from 40 the driver's compartment or at some other remote point in a vehicle driven by the governed engine.

45 Other and further features and objects of the invention will be more apparent to those skilled in the art upon a consideration of the accompanying drawings and following specification, wherein are disclosed several exemplary embodiments of the invention, with the understanding that such changes, modifications and combinations of the disclosed features may be made as fall within the scope of the appended claims without departing from the spirit of the invention.

In said drawings:

50 Fig. 1 is a side elevation of a governor ac-

cording to one feature of this invention with parts of the housing cut away on the axis of the spring to show the adjusting mechanism;

Fig. 2 is a horizontal section on broken line 2—2 of Fig. 1;

Fig. 3 is a section on line 3—3 of Fig. 1;

Fig. 4 is a section on line 4—4 of Fig. 2;

Fig. 5 is a fragmentary section on the axis of and showing a modified means for operating the adjusting screw;

Fig. 6 is a section on line 6—6 of Fig. 5 showing the application of sealing means to secure the adjustment;

Fig. 7 illustrates in longitudinal section remote-control mechanism substituted for the adjusting means of Fig. 5; and

Fig. 8 is an elevation of an alternative form of the key control mechanism for a remote-control adjusting device.

Fig. 9 is a view similar to Fig. 5 showing a further modification.

Governors for internal combustion engines of the type commonly known as "suction-operated" comprise a casing including a passage to be inserted between the carburetor and intake manifold of the engine and containing the governor valve. This valve is, in most cases, urged toward open position by a spring or other means to counteract the closing effort of the suction of the engine suitably applied thereto. Because the varying pressures occurring in the intake manifold are non-linear in respect to engine speed and/or power, the closing effort, however it may be applied to the valve, cannot be resisted by a simple spring directly connected to the valve or its stem. Some means must be interposed between the spring and the valve to compensate for the linear variation in the resistance of the spring and the non-linear force acting to close the valve in order that the governor may maintain such a valve position for all power outputs of the engine as to insure close governing.

Long experience with such governors indicates that they must be carefully designed, each for its particular engine and the spring must have a definite tension and rate or flexibility for each governed speed. This has heretofore made it difficult to adjust a governor to operate at various points over a considerable range of speed without substituting a different spring for each speed, so it has become the custom to fix the governed speed within a fairly close range and not to provide any substantial adjustment.

Under the conditions outlined above, an operator of a fleet of motor vehicles or the owner of

one or more vehicles buys a governor for each of them adjusted, say, to thirty miles per hour or whatever speed he desires the vehicle to be operated. But in many cases it is desirable under different operating conditions to permit the vehicle to be run at different maximum speeds and it is the object of the present invention to provide means whereby governors of the type described can be readily adjusted to operate over a wide range of speeds without in any manner reducing the effectiveness of the governing at any of these speeds.

Attempts to adjust the previously known types of governors for different governing speeds has had detrimental effects on the closeness of governing because in most cases only the tension or resistance of the spring could be adjusted. The present invention is shown as applied to a form of governor which has achieved a wide use in the art and which is disclosed basically in the patent to Handy and Bull No. 1,584,929.

Referring to Figs. 1 and 2 of the accompanying drawings, this governor is seen to include a casing 10, having the passage 11 adapted to be interposed between the carburetor and intake manifold of an engine and adjustable from open to closed condition by a butterfly valve 12 asymmetrically mounted on the eccentrically positioned shaft 13 whereby the action of the combustible gases passing through the passage tends to close the valve. The closing is resisted by the helical spring 14 associated with the extended end of the shaft valve 13 by the flexible tape 15 having its opposite end attached at 16 to an arm 17 on the valve shaft. The spring and its associated mechanism are arranged in the compartment 10' associated with the casing 10. The tape 15 passes over the cam surface 18 extending from the arm 17 so that the force of the spring is applied through varying radii to resist the closing effort of the valve. The shape of the surface 18 is carefully determined for the particular characteristics of the engine with which the governor is to be used.

The end of the spring 14 opposite to that attached to the tape is anchored by adjusting mechanism forming the essential feature of the present invention. An extension 20 of the casing 10 is preferably formed integral therewith and is of tubular formation to house the adjusting screw 21 and its kerfed head 22. This screw carries at the inner end a rigidly mounted nut 23 whose outer surface is threaded to receive the convolutions of the spring 14. The screw is threaded into a nut 24 rotatably mounted in a restricted portion 25 of the extension 20 but restrained against longitudinal movement therein by having a head bearing against a shoulder at the junction of the restricted portion and the cylindrical bore 26. The screw head 22 is provided with detent mechanism to hold it securely in adjusted position. This may take the form of a spring-pressed ball 27 urged into a series of shallow grooves 28 extending longitudinally of the interior of the bore 26. If it is desired to lock the adjustment after it has been made by a screw driver, a Welsh plug 29 may be driven into the end of the opening.

The pitch of the thread 30 on the screw 21 is greater than the pitch of the thread on the nut 23 whereby when the adjusting screw is advanced to the right, by suitable rotation, the nut 23 moves into the coils of the helix at a slower rate than it advances to the right, so that the tension of the spring is reduced as its rate is

increased, that is, the spring becomes less flexible as its tension is reduced and vice versa. In order to prevent the spring from rotating or twisting as the nut 23 is threaded into it, the end of the wire forming the spring is bent radially outwardly as shown at 32 in Figs. 2 and 4, and is constrained against rotation but permitted to move longitudinally in the groove 33 between the rails 34 preferably cast integral with the housing.

For every speed of the engine for which it is desired to have governing, there is a definite tension and flexibility of the spring which must be effected. The adjustment just described provides for such change in the rate and tension of the spring, for the whole is designed with a predetermined pitch to the threads on the nut 23 and on the screw 21 to assure the proper rate and tension for each of the speeds for which the governor is adaptable. However, during the assembly of the governor and sometimes in later adjustments, it is essential that the initial tension be properly set so that thereafter the tension and rate vary in the predetermined manner.

This is simply effected by rotation of the nut 24 which allows the screw 21 to be moved longitudinally without rotation, thus changing only the tension of the spring. The periphery of the nut, intermediate its ends, is provided with a suitable thread or more simply, it is just knurled as at 35 in Fig. 3 to cooperate with the threads 36 of a screw 37 loosely fitting in the cylindrical bore 38 and having the same overall length as the depth of this bore. Rotation of this screw, by a suitable tool, imparts slow rotation to the nut and thus permits minute adjustments of spring tension to be made. The head of the screw is concealed by the cover plate 39 closing the compartment 18 and attached by screws to which a seal may be applied to prevent tampering with the adjustment.

Where it is desired to be able to occasionally change the adjustment to permit the engine to be run at a different maximum speed, the adjusting mechanism shown in Figs. 5 and 6 may be resorted to. Here the projection 20' on the governor housing is truly cylindrical and the screw 21' having the head 22' is provided with a non-circular longitudinal bore 40 into which is slidably fitted a corresponding cross-sectioned rod 41, projecting from the center of the head 42 of a cap 43 for the end of the projection 20'. Obviously, rotation of the cap imparts rotation to the screw which is permitted to move longitudinally in respect to the cap and rod because of the sliding fit. The cap is provided with a series of circumferentially disposed holes 44 in the flange thereof and the extension 20' is provided with a chordal slot 45 the ends of which substantially coincide with a pair of holes 44 so that a wire 46 from the seal 47 may be passed therethrough to prevent further adjustment of the device without breaking the seal.

In certain types of vehicles operated by internal combustion engines it may be desirable to adjust the governed speed of the engine from the driver's compartment. For instance, a parent may desire to be able to drive the vehicle at substantially its maximum speed, but when allowing the same to be used by some of his children may wish to limit the speed at which they can operate the same, so there is provided in accordance with Figs. 7 and 8, a remote control for the governor which takes the place of the cap and adjusting pin just described. In Fig. 7 the heavier cap 50 fits over the extension 20' of the gov-

ernor casing and is secured in position by a similar seal. This has extended from its outer end a flexible sleeve 51 housing the flexible cable 52. This cable has secured to the end which passes

5 through the cap, the pin 41² for adjusting the screw 21² as previously described. The flexible cable and conduit may pass through a rubber grommet 53 in the dash of the vehicle. There is attached to the opposite end of the cable the dash mounted mechanism 54 including the key actuated lock mechanism 55 which can be locked in any position by the withdrawal of the key so that it cannot be rotated in respect to the casing. This permits the insertion of the key and the

10 rotation thereby of the lock mechanism to adjust the speed setting of the governor and the withdrawal of the key to lock the setting. If it is not desired to mount the locking device on the dash, it may be mounted on and beside the 15 steering column as shown in Fig. 8 where the locking head 56 is attached to a band 57 adapted to be clamped around the steering column by a bolt 58. The wire 59 from a seal 60 passes through a hole 61 in the bolt and a second hole 25 62 in the tongue of the strap 57 to prevent the bolt from being rotated to loosen the strap.

In Figure 9 is shown a further embodiment where the key controlled lock is mounted directly on the tubular extension 20³. The construction here may be considered as substantially identical to Figure 7 with the flexible cable omitted. The sleeve 70 which carries the rotatable lock barrel 71, operable by the key 72, is adapted to slide over the projection 20³ and to 30 be secured in position thereon by the seal wire 46³ exactly as shown in Figures 5 and 6. The lock barrel 71 is provided with the non-circular rod 72 extending rearwardly therefrom and adapted to be slidably received in the opening 40³ in the 35 adjusting screw 21³.

This type of adjusting mechanism is convenient where changes in governed speed are often required but where the expense of the form shown in Figure 7 is not warranted, nor the 40 continued removing and replacing of the seal is not desired, as in Figures 5 and 6, every time an adjustment is to be made. Keys can be furnished to those authorized to make adjustments and the adjustment can be simply made on lifting the 45 hood of the vehicle, applying the key and rotating it the required number of turns, after which it is removed, and the adjustment is fixed until the key is again used.

50 Any of the devices described permit accurate adjustment of both the tension and flexibility of the spring, permit initial adjustment of the tension, and insure proper speed control for any setting of the governor.

55 In the patent to Bull No. 2,048,423, for Stabilizer for suction governors, there is disclosed an arrangement of auxiliary piston exposed to atmosphere on one face and to the pressure on the up-stream side of the governing valve on the other, and connected to augment the closing effort of the governing valve. Such a piston is effective only throughout a relatively small arc of movement of the valve from open position. At 60 open position, the forces tending to close the valve are otherwise a minimum and the piston is a valuable aid in starting the valve toward closing position, thereby preventing "stealing" and making the governor more sensitive under heavy loads and at high speeds.

65 In accordance with the present invention, a piston of similar function is incorporated in a

novel manner. This piston is shown at 70 in Fig. 2 operating in a cylindrical chamber 71 formed in the valve casing and having its outer end closed by a suitable head 72. The piston is secured to a rod or stem 73 guided in a bore 14, leading into the passage 11 which houses the valve 12. The bore 14 is sufficiently loose so that pressure existing on the up-stream side of the governing valve (the governor shown is for down draft carburetors) is imparted to the inner face 10 of the piston. The outer face of the piston is exposed to atmosphere through the restricted passage 75 and the air filter 76 as shown.

The piston is only effective at and near open positions of the valve and in order to eliminate the frictional effects thereof when the valve is nearly closed and when great sensitivity is desired, there is no positive connection between the piston and the valve as in the patent referred to. A one-way connection is provided by mounting the abutment 77 on the valve plate 12, against which the end 78 of the rod 73 impinges as shown in Fig. 1. It is obvious that the valve can move ahead of the piston and operate independently thereof and to insure that the small negative pressure on the inside of the piston does not keep the rod in contact with the valve abutment at all times, a light spring 79 surrounds the valve stem 73 between the inner face of the piston and the opposite end of the cylinder in which it operates. Sufficient resistance is built up by this spring as the piston moves to the right to insure against contact between the rod end 78 and the abutment 77 after the valve has moved approximately 45° from open position.

Having thus described the invention, what is claimed as new and desired to be secured by Letters Patent is:

1. A device for changing the flexibility and tension characteristics of a spring controlling the butterfly valve in the intake manifold of an internal combustion motor comprising means including a helical spring acting between an anchor and said valve counterbalancing the effort thereof at a predetermined speed of the motor and in all positions thereof, said anchor comprising a screw having a fixed head threaded for engagement with the coils of said spring, a nut threaded on said screw and mounted for rotation only, means to rotate said screw in the nut and spring, and means to rotate the nut about the screw.

2. A device for changing the flexibility and tension characteristics of a spring controlling the butterfly valve in the intake manifold of an internal combustion motor comprising means including a helical spring, and means to adjust the flexibility and tension of said spring comprising a screw having a fixed head threaded for engagement with the coils of said spring, a nut threaded on said screw and mounted for rotation only, means to rotate said screw in the nut and spring, and means to rotate the nut about the screw.

3. A device for changing the flexibility and tension characteristics of a spring controlling the butterfly valve in the intake manifold of an internal combustion motor comprising means including a helical spring acting between an anchor and said valve counterbalancing the effort thereof at a predetermined speed of the motor and in all positions thereof, said anchor comprising a screw 70 having a fixed head threaded for engagement with the coils of said spring, a nut threaded on said screw and mounted for rotation only, means to rotate said screw in the nut and spring, and means to rotate the nut about the screw, the pitch 75

of the screw thread being greater than the pitch of the thread on the head which engages the spring.

4. A device for changing the flexibility and tension characteristics of a spring controlling the 5 butterfly valve in the intake manifold of an internal combustion motor comprising means including a helical spring, and means to adjust the flexibility and tension of said spring com-

prising a screw having a fixed head threaded for engagement with the coils of said spring, a nut threaded on said screw and mounted for rotation only, means to rotate said screw in the nut and spring, and means to rotate the nut about the screw, the pitch of the screw thread being greater than the pitch of the thread on the head which engages the spring.

HERMAN G. ADLER.
